(57) **CLAIM**

The ornamental design for a knife handle, substantially as shown and described.

DESCRIPTION

FIG. 1 is an isometric view of a knife handle, showing my new design.

FIG. 2 is a right side elevational view thereof.

FIG. 3 is a left side elevational view thereof.

FIG. 4 is a top plan view thereof.

FIG. 5 is a bottom plan view thereof.

FIG. 6 is a front elevational view thereof; and,

FIG. 7 is a rear elevational view thereof.

Shading lines shown in the drawings are intended to represent the approximate three-dimensional contour of the design, and are not intended to indicate surface decoration. The broken lines in the figures are for illustrative purposes only and form no part of the claimed design.
